UNITED STATES PATENT OFFICE.

ROBERT H. PLASS, OF UPPER MONTCLAIR, NEW JERSEY.

WEB-PRINTING DEVICE.

1,305,235.

Specification of Letters Patent. Patented May 27, 1919.

Application filed November 24, 1917. Serial No. 203,662.

To all whom it may concern:

Be it known that I, ROBERT H. PLASS, a citizen of Germany, residing in the city of Upper Montclair, county of Essex, and 5 State of New Jersey, have invented certain new and useful Improvements in Web-Printing Devices, of which the following is a full, clear, and exact specification.

My invention relates to web printing devices and refers particularly to a device whereby impressions may be printed upon a continuous web at predetermined distances from each other, irrespective of the diameter 10 of the printing rollers.

One object of my invention is a device whereby printed impressions may be made upon a web at predetermined distances from each other.

Another object of my invention is a device 20 whereby printed impressions may be made upon a web at distances irrespective of the diameter of the printing roller.

Another object of my invention is a device in which a printing roller may be employed 25 to produce printed impressions upon a web at any predetermined distance from each other.

Another object of my invention is a web printing device which is capable of printing 30 impressions at varying distances from each other.

These and other objects of the device of my invention will be evident upon a consideration of my specification and claims.

In the generally employed methods of printing upon webs, the type or other printing means are affixed to the outer surface 35 of a revoluble roller or cylinder, the web passing between said roller and a platen.

In this manner the web receives a printed 40 impression upon each revolution of the roller, and hence the impressions are equally distant from each other, the distance between them being represented by the circumference of the roller.

It is frequently desirous to print the impressions at a distance from each other greater than the circumference of the printing roller, this requirement being particularly 45 important where the web is afterward cut into desired lengths, as in the production of bags.

In the machines described above the distance between the printed impressions is a 50 fixed one dependent upon the circumference of the printing roller and hence a printing

roller of definite circumference must be employed in the printing of bags of each particular size in order that the impressions may be uniformly printed upon all of the 60 bags, and as all of the other component parts of the machine are in uniformity with the printing roller, a separate machine is necessary for use upon each class of work.

I overcome this serious difficulty by presenting a machine that will permit impressions upon a web at any predetermined distance from each other irrespective of the size 65 of the printing roller, thus allowing the one machine to be used in the printing of bag- 70 webbing for any desired size of bags.

The advantages of the device of my invention and its economical production of web printing as regards labor, time, space and rapidity of out-put are evident upon a 75 consideration of my specification.

In a broad way my invention comprises a device whereby any predetermined length of the web may be drawn past the printing roller during the neutral or non-printing 80 period of the roller, thus allowing the printed impressions to be separated from each other by a distance greater than the circumference of said roller.

In the particular form of the device of 85 my invention illustrated in the accompanying drawings, similar parts are designated by similar numerals:—

Figure 1 is an end plan view, partly in section.

Fig. 2 is an enlarged elevation of Fig. 1 with side frame removed, partly broken and partly in section.

Fig. 3 is a cross-section through the line 3—3 of Fig. 2.

Fig. 4 is a cross-section through the line 4—4 of Fig. 3.

The particular form of the device of my invention as shown in the accompanying drawings, comprises a power driven revoluble shaft 10 carrying the spur-gear 11, which meshes with the spur-gear 12 carried by the revoluble shaft 13. The spur-gear 12 meshes with the spur-gear 14 carried by the revoluble shaft 15, which in turn meshes with the 100 spur-gear 16 carried by the revoluble shaft 17, and the spur-gear 18 carried by the revoluble shaft 19. The spur-gear 18 meshes with the spur-gear 20 carried by the revoluble shaft 21, which in turn meshes with the 105 spur-gear 22 carried by the revoluble shaft 23. The shaft 21 carries the platen roller

24, and the shaft 23 carries the roller 25 having the printing means 26 upon a portion of its perimeter. The shaft 15 carries the platen roller 27, and the shaft 17 carries the roller 28 having the printing means 29 upon a portion of its perimeter, the position of the platen rollers and the printing rollers being such that a web 100 carried between them during their revolution will receive printed impressions. Meshed with the spur-gear 12 is the spur-gear 30 fixedly attached to the revoluble shaft 31. The shaft 31 carries the cam 32 fixedly attached thereto. Revolubly carried by the frame 33, 33 of the device is the rock shaft 34. Fixedly attached to the rock shaft 34 is the cam arm 35, upon the portion 36 of which the cam 32 abuts. Fixedly attached to the rock shaft 34 are the arms 37, 37, to the other ends of which are pivotally attached the links 38, 38, the latter being pivotally attached to the shaft 39, revoluble in the slide bearing 40, and carrying the roller 41, the slide bearing 40 being capable of a vertical movement within the track supports 42, 42. Capable of being revolved by the revolution of the spur-gear 30 is a series of spur-gears 43, 44, 45, 46, 47, 48 and 49. The spur-gear 47 is fixedly attached to a shaft carrying the roller 50, and the spur-gear 49 is fixedly attached to a shaft carrying the roller 52. Abutting upon the rollers 50 and 52 and frictionally revoluble therewith is the roller 51, held in abutment by means of the spring 53. A set screw 55 abutting upon one of the arms 37 determines the length of the movement of the arms 37, 37 and the roller 41, and the stop pin 56 prevents the arms 37, 37 and the roller 41 from dropping too far when the web 100 is removed. Revoluble idlers 57, 58, 59, 60 and 61 are introduced into the path of the web 100.

If it is desired to change the speed of the rollers 50, 51 and 52, the set screw 90 is loosened, the frame 91 revolved upwardly, and the spur-gear 46 replaced by one of the desired size, the frame 91 lowered until the introduced spur-gear meshes with the spur-gear 47 and the set screw 90 tightened.

The operation of the device is as follows:—

When the platens 24 and 27 and the printing rollers 25 and 28 are revolved by means of the spur-gear 11 through the series of connecting spur-gears, the web 100 is drawn over the idlers 57, 58 and 59 and printed at approximately the same portion of the web by the printing means 26 and 29. The mechanism is synchronized so that when the platens and printing rollers are in position shown in Fig. 2, leaving a space between the platens and the printing rollers, the cam 32 will move downwardly, carrying with it the members 37 and 38 and the roller 41 from the full line positions to the dotted line po-

sitions, thus pulling an amount of web between the platens and the printing rollers, the amount being predetermined by the length of the stroke of the roller 41 as governed by the position of the set screw 55. The roller then returns to its extreme upper position and the loose web thus produced passes between the rollers 50, 51 and 52 and the idler 61, the speed of the rollers 50, 51 and 52 being so fixed as to take up and carry away the loose web during the next printing process, so that when the printing means have again completed their operation, the loose web will have been disposed of and the operation of drawing another portion of web can be accomplished. As the roller 51 is held in frictional abutment against the rollers 50 and 52, thus holding the web 100 during the downward movement of the roller 41, the web 100 will be drawn from the folded web supply resting upon a suitable platform 101 and hence drawn between the platens 24 and 27 and the portions of the printing rollers 25 and 28 not carrying the printing means 26 and 29.

It is evident that the device will thus withdraw the web evenly and quickly without sudden jerks, thus producing positive and uniform results.

I do not limit myself to the particular size, shape, number or arrangement of parts as described and shown, all of which can be varied without going beyond the scope of my invention as described and claimed.

What I claim is:—

1. In a web printing machine, in combination, a revoluble web printing means capable of conveying a web, means for revolving the web printing means, conveying means for conveying the web after printing preventing the return movement of the web, accelerating means between the printing means and the conveying means and a cam movement whereby the speed of the web may be accelerated past the printing means during non-printing periods.

2. In a web printing machine, in combination, a revoluble web printing means capable of conveying a web, means for revolving the web printing means, conveying means for conveying the web after printing preventing the return movement of the web, movable means abuttable upon the web between the printing means and the conveying means and a cam movement for moving the movable means at predetermined periods accelerating the movement of the web past the printing means.

3. In a web printing machine, in combination, a revoluble web printing means capable of conveying a web, means for revolving the web printing means, conveying means for conveying the web after printing preventing the return movement of the web, movable means abuttable upon the web be-

tween the printing means and the conveying means and a cam movement for moving the movable means coincident with a non-printing period withdrawing a predetermined length of web past the printing means.

4. In a web printing machine, in combination, a revolute web printing means capable of conveying a web, means for revolving the web printing means, conveying means for conveying the web after printing preventing the return movement of the web, accelerating means for accelerating the movement of the web at predetermined periods and a cam movement synchronizing the action of the accelerating means with the non-printing periods of the printing means.

5. In a web printing machine, in combination, a revolute printing cylinder capable of conveying a web, means for revolving the cylinder, printing means upon a portion of the perimeter of the cylinder, a platen, conveying means for conveying the web after printing preventing the return movement of the web, an accelerating member between the printing cylinder and the conveying means transverse of the web and a cam movement for rendering the accelerating member operative at predetermined periods withdrawing a predetermined length of web from between the printing cylinder and the platen during non-printing periods.

6. In a web printing machine, in combination, a revolute printing cylinder, means for revolving the cylinder, printing means upon a portion of the perimeter of the cylinder, a platen, conveying means for conveying the web after printing preventing the return movement of the web, an accelerating member between the printing cylinder and the conveying means transverse of the web, a cam movement synchronized with the non-printing periods moving the accelerating member and withdrawing a length of web past the printing cylinder, means for regulating the length of the web withdrawn and means for the movement of the web during printing periods.

50 7. In a web printing machine, in combination, a revolute printing cylinder capable of conveying a web, means for revolving the cylinder, printing means upon a portion of the perimeter of the cylinder, a platen, a

series of revolute conveying rollers for conveying the web after printing preventing the return movement of the web, means for revolving the conveying rollers, an accelerating member between the printing cylinder and the conveying rollers transverse of the web and abuttable thereon, a cam movement for moving the accelerating member from its normal inactive position during non-printing periods withdrawing web past the printing cylinder and means for predetermining the length of web withdrawn.

8. In a web printing machine, in combination, a revolute printing cylinder, means for revolving the cylinder capable of conveying a web, printing means upon a portion of the perimeter of the cylinder, a platen, a series of revolute conveying rollers for conveying the web after printing preventing the return movement of the web, means for revolving the conveying rollers, an accelerating member between the printing cylinder and the conveying rollers transverse of the web and abuttable thereon, a cam movement synchronized with the non-printing periods moving the accelerating member and withdrawing web from between the printing cylinder and the platen during non-printing periods, means for regulating the length of movement of the accelerating member, and means for returning it to its inoperative position during printing periods.

9. In a web printing machine, in combination, a series of revolute printing cylinders capable of conveying a web and having printing means upon a portion of their perimeters, a series of platens, means for revolving the printing cylinders and the platens, conveying means for conveying the printed web and preventing the return movement of the web, an accelerating member between the printing cylinders and the conveying means and a cam movement synchronized between the printing cylinder and the accelerating member whereby a predetermined length of web will be withdrawn between the cylinder and the platens during non-printing periods.

Signed at Jersey City, in the county of Hudson and State of New Jersey, this 22nd day of November, 1917.

ROBERT H. PLASS.
